ELECTRONIC COUNTING CIRCUITS

Joseph W. Kennedy, Santa Fe, N. Mex., William R. Baker, Berkeley, Calif., and Clyde E. Wiegand, Santa Fe, N. Mex., assignors to the United States of America as represented by the United States Atomic Energy Commission

Application April 24, 1944, Serial No. 532,566

4 Claims. (Cl. 250—83.6)

1

The present invention relates to electronic devices and more particularly to an improved electronic counting circuit.

It is an object of the present invention to provide an electronic counting circuit that is both simple and compact in its construction and is positive in its operation.

Another object of the present invention is to provide a pulse counting circuit network that is portable and entirely self-contained.

Still another object of the present invention is to provide an electronic device for counting ionizing particles, such as alpha or beta particles, which device is entirely portable.

Still another object of the invention is to provide a counting device that has incorporated therein an integrating arrangement, the accuracy of the integrating arrangement being substantially independent of the time interval between the integrated pulses.

Other objects of the present invention will be apparent from the following description and the accompanying drawing which illustrates a preferred embodiment thereof.

The drawing is a schematic view of an improved counting mechanism that embodies the present invention and essentially comprises a battery source of potential and an arrangement for amplifying the battery potential to a voltage sufficiently high for use with an ionization chamber incorporated in the counting mechanism. The pulses resulting in the ionization chamber are amplified by a multi-stage linear amplifier of variable sensitivity, the output of which is fed either directly or through an integrator to a discriminator stage. The purpose of the discriminator stage is to distinguish between pulses of the desired counted particles and other ionizing particles or radiation or other background noises which are necessarily present. The output of the discriminator stage in turn triggers a grid-controlled gas discharge tube which actuates an electrical recording device or register.

Referring to the drawing, the present device includes a power supply comprising a filament battery 2 of 1.5 volts, plate supply series-connected batteries 3 totaling 135 volts, and a 45-volt grid bias supply battery 4 having a 22-volt tap. The negative terminal of the plate supply batteries 3 and the positive terminal of the grid bias supply battery 4 are grounded through an octal connector 8. The other terminals of the plate supply batteries 3 and the filament battery 2 are also connected to the circuit through the octal connector 8.

The arrangement for amplifying the voltage of the plate supply battery to the high potential required for an ionization chamber 7 comprises tubes V8 and V9 and their associated circuit networks. Although the tube V9 may be a glow dis-

charge tube, in the present embodiment it is shown as a cold cathode thyratron, the plate of which is unemployed, the control grid thereof acting as one electrode and the cathode thereof as the other electrode. One terminal of the primary of the transformer 91 is connected to the control grid 95 of the tube V9, the other terminal thereof being connected to the high positive terminal of the plate supply batteries 3 through a 0.10-megohm resistor 96, switches 92 and 94, and the octal connector 8. The transformer end of the resistor 96 is connected through a 1-microfarad condenser 97 to the cathode 98 of the tube V9, which cathode is in turn grounded. It should be noted that the control grid lead and the cathode lead of tube V9 are shielded. A terminal of the secondary of the transformer 91 is connected to the plate 85 of the tube V8, the other terminal thereof being grounded. The tube V8 is shown as a triode wherein the grid and filament are tied together, thus practically resulting in a diode, but it is apparent that an ordinary diode may be used in its stead. The filament 86 of the tube V8 is supplied current by a battery 81 through a switch 82, the filament 86 being connected through a 10-megohm resistor 83 to the electrode 6 of the ionization chamber 7, the two terminals of the resistor 83 being grounded through .05-microfarad condensers 84, the resistor 83 and condensers 84 forming a filter network. The other electrode 9 of the ionization chamber 7 is connected to the control grid 10 of a tube V1, the filament of the tube V1 being connected to ground and through a switch 11 to a filament supply bus. Although the tube V1 is shown as a pentode having its suppressor grid tied to the filament and its screen grid connected through a 1-megohm resistor 12 to the 45-volt positive potential and being by-passed to ground through an 8-microfarad condenser 13, it is obvious that other types of tubes may be substituted in its place. In this first stage a tube having a very low noise level is required, inasmuch as the pulses supplied to the control grid thereof are very weak. It has been found that a 959 type of Acorn tube is satisfactory. The plate of the tube V1 is connected to series-connected resistors 14 and 16, the resistor 16 being of 0.1-megohm and the resistor 14 being of .05 megohm and through a switch 94 to the 45-volt positive potential. The junction point between resistors 14 and 16 is grounded through an 8-microfarad decoupling condenser 17. The plate of the tube V1 is also connected through a .0005-microfarad coupling condenser 18 to the control grid of a pentode V2, which control grid is grounded through a .25-megohm resistor 20. The suppressor grid of the pentode V2 is tied to the filament thereof, which filament is in turn connected to the filament supply bus. Connected in the usual manner through

a by-pass condenser 23 to ground and through resistor 22 to the high positive plate supply bus is the screen grid of the pentode V2, the anode being supplied a positive potential from the high voltage bus through the resistors 25 and 26, the junction point between the resistors 25 and 26 being grounded through a decoupling condenser 27. The anode of the pentode V2 is also connected to ground through a coupling condenser 28 and the tapped potentiometer resistor 29. The values of the resistors and condensers of the stage including the pentode V2 are those usually employed, the by-pass condenser 23 being of .8 microfarads, the resistor 22 of 1.5 megohms, the resistor 26 of .25 megohm, the resistor 25 of .05 megohm and the condensers 27 and 28 being .8 microfarads and .01 microfarad respectively. The following two stages of amplification have substantially the same element values.

Connected to the adjustable arm of the potentiometer 29 is the control grid of the pentode V3, the filament of which is connected to the filament supply bus and has tied thereto the suppressor grid. The screen grid of the pentode V3 is connected through a resistor 32 to the high positive plate potential bus and is grounded through a by-pass condenser 33. The plate of the pentode V3 is supplied a positive potential through series-connected resistors 35 and 37, the junction point of which is grounded through a decoupling condenser 34. The output of the pentode V3 is connected through a coupling condenser 39 through a potentiometer resistor 40 to ground, the adjustable arm of the potentiometer being connected to the control grid of a tube V4. The filament, suppressor grid and screen grid of the tube V4 are connected in a manner similar to the connections in the pentode V3, the plate voltage being applied through a resistor 41 and an impedance element 42, the inductive impedance of the impedance element being about 60,000 ohms at 1000 cycles. The output of the tube V4 is connected through a coupling condenser 43 and switches 44 and 45 to the junction point of .01-microfarad condensers 50 and 51, the other terminal of the condenser 51 being connected to one pole of a switch 52 and the other terminal of the condenser 50 being connected to the control grid of a pentode V5.

The control grid of the pentode V5 is supplied a 22-volt negative bias through a 1-megohm resistor 53. The suppressor grid of the pentode V5 is tied to the filament, which in turn is connected to the filament supply bus, the screen grid of the pentode V5 being grounded through the by-pass condenser 54. Also connected to the screen grid is the adjustable arm 55 of a 10-megohm potentiometer 56, one terminal of the potentiometer 56 being grounded and the other terminal being connected through a switch 57 to the 90-volt positive potential of the plate supply batteries 3. The anode of the tube V5 is connected to the 90-volt positive potential through a condenser 58 in parallel with a series-connected .02-megohm resistor 59 and glow discharge lamp 60, which glow discharge lamp may be of the ordinary neon or argon type. It should be noted that the anode of tube V5 is, except for negligible leakage, in an isolated condition.

The junction point between the resistor 59 and the glow discharge lamp 60 is connected through a coupling condenser 61 to a pole 63 of the switch 52, which pole is grounded through a 1.0-megohm resistor 64. Connected to the blade of switch 52 is the control grid of a tube V6,

which control grid is supplied a negative bias of 22 volts through a 2-megohm resistor 65. The filament of the tube V6 is connected to the filament supply bus and has tied thereto a suppressor grid, the screen grid being grounded through a condenser 66 and being connected through the switch 57 and a .25-megohm resistor 68 to the 90-volt positive plate potential, the same potential being applied to the anode of the tube V6 through a .25-megohm resistor 69. The output of the tube V6 is led through a coupling condenser 70 to the control grid of a gas discharge tube V7, which control grid has a negative 45-volt bias applied thereto through a 1-megohm resistor 71. The cathode and anode of the tube V7 are shunted by a 1-microfarad condenser 72, the anode being connected through an electromagnetic register 73, a .0025-megohm resistor 74 and the switch 45 to the high positive plate potential, the cathode being connected directly to ground. The register 73 may be of any well-known electromagnetic type that has a substantially high counting rate.

The improved counting device has been described and specific values applied to the component parts thereof, but it is obvious that these values, as well as the component parts thereof, may be changed or altered to suit a particular purpose. For example, the ionization chamber has been illustrated merely as a pair of electrodes; however, it should be understood that any other well-known type of ionization chamber may be used, such as a proportional counter, as well as a Geiger-Muller tube supplied with external or internal quenching. Also the design of the amplifier may be modified, but in any case the amplifier should be one having a low noise level and a high degree of stability with respect to overall gain.

The device operates as follows. The high voltage plate supply is fed to the stage comprising the tubes V8 and V9, the tube V9 and its associated elements acting as a relaxation oscillator forming high voltage periodic pulses having a steep wave front, which pulses are in turn amplified by the step-up transformer 91 and thence rectified and filtered by the tube V8 and the resistor condenser network resulting in a voltage output of the order of 1500 volts. The positive potential output of the supply is applied to the electrode 6 of the ionization chamber, the other electrode 9 being connected to the grid of tube V1. There is a high potential existing between the electrodes of the ionization chamber 7 and any ionizing particle introduced between these electrodes will produce ionization of the gas between the electrodes 6 and 9, resulting in a momentary surge of current which impresses a pulse on the control grid of the tube V1. This pulse is amplified through the four stages of amplification including the tubes V1, V2, V3 and V4, the sensitivity of the amplifier being adjustable by means of the potentiometers 29 and 40. The scaling circuit including the tube V5 integrates the output pulses of the last stage of the amplifier, the output of the scaling circuit or the output of the amplifier being fed through the double throw switch 52 to the discriminator stage including the tube V6. The condenser 58 of the scaling circuit is step charged for each pulse applied to the control grid of the tube V5. The condenser 58 will retain its charge except for negligible leakage. Inasmuch as the anode of the tube V5 and the side of the condenser 58 connected thereto is in an isolated condition except

for the aforesaid negligible leakage, the condenser 58 has no discharge path except through the gas tube 60 upon firing. When the potential across the condenser 58 reaches a predetermined voltage the condenser will discharge through the gas tube 60, thus sending a pulse through the condenser 61. It is obvious that the frequency of discharge of the condenser 58 is dependent upon the frequency of the pulses fed to the control grid of tube V5, as well as upon the duration and intensity of these pulses. The aforesaid can be varied by means of the potentiometers 29 and 40 of the amplifier. By adjusting the potentiometer 56, the scale of the integrator may also be changed. The discriminator stage consists of the tube V6 biased beyond cutoff, which tube is responsive only when a pulse of a predetermined voltage is applied to its control grid. In this way any undesired pulses which are below the predetermined voltage will have no effect on the subsequent stages of the counter.

The output of the discriminator stage triggers the cold cathode thyratron V7 which in turn becomes conducting, causing the condenser 72 to discharge, thereby allowing the thyratron V7 to de-ionize, thereby returning the grid thereof to control. Thereafter the condenser 72 is charged through the resistor 73 and the resistor 74, causing the register 73 to advance. More specifically, the time constant of the resistor-condenser network 74-72 is of such value as to permit the thyratron V7 to de-ionize before the potential on the condenser 72 reaches a value sufficient to maintain the thyratron discharge, thereby allowing the grid of the thyratron V7 to regain control.

Considering now the calibration and application of the improved apparatus, a standard sample having a known count is positioned between the electrodes 6 and 9 of the ionization chamber 7 and the gain of the amplifier is adjusted by means of the potentiometers 29 and 40. The scaling circuit is adjusted to any desired value by varying the potentiometer 56, thus establishing the screen grid potential of the pentode V5. An apparatus count is then taken of the standard sample and by comparing the known count of the standard sample with the apparatus count the calibration factor of the apparatus at the set adjustments is determined. Thereafter the standard sample is removed and the test sample, the count of which is desired, is inserted between the electrodes 6 and 9 of the ionization chamber 7 and the apparatus count is obtained. By multiplying the apparatus count of the test sample by the calibration factor the absolute count of the test sample can thus be determined.

Of course, the kind and mean energy of the particles emitted by the standard sample should be substantially the same as of the particles emitted by the test sample, and the effective thickness of the two samples should be substantially the same, so that energy losses within the sample are the same on the average, for the two samples, and the samples should be so positioned that the average path length of the particles within the ionization chamber is the same for the two samples. For example, if it is desired to count alpha particles from a test sample containing unknown amounts of the uranium isotope, it would be adequate for approximate work to use as a standard sample one containing a known amount of uranium having the normal ratio of isotope concentrations, since the alpha particles from these isotopes all have the same

energies within about 15%. However, it probably would not be satisfactory to use polonium or a beta-emitter for the standard sample. If furthermore the thicknesses of the standard and test samples are not more than about 10^{-5} cm., energy losses within the samples can be ignored altogether. Care should of course be exercised that the amplifier does not change appreciably between calibration and use.

10 A preferred embodiment of the invention has been shown, but it is obvious that numerous alterations and omissions may be made without departing from the spirit thereof.

What is claimed is:

1. A self-contained portable counter comprising an ionization chamber, a power supply for furnishing a high potential to said ionization chamber, a pulse amplifier, a scaling circuit the input thereto being the amplified pulses, a register, and switching means for impressing the output of the scaling circuit or the amplified pulses to said register.
2. A self-contained portable counter comprising an ionization chamber, a power supply for furnishing a high potential to said ionization chamber, a pulse amplifier, a scaling circuit the input thereto being the amplified pulses, means for varying the scale of said scaling circuit, a register, and switching means for impressing the output of the scaling circuit or the amplified pulses to said register.
3. A self-contained portable counter comprising in combination an ionization chamber, a battery source of potential, electronic means for amplifying said potential, means for applying said amplified potential to the electrodes of said ionization chamber, a preamplifier stage controlled by the output of said ionization chamber, a pulse amplifier, the output of said preamplifying stage feeding said pulse amplifier, a scaling circuit, an electromagnetic register, and switch means for selectively conducting the output of said pulse amplifier directly or through said scaling circuit to said register.
4. In a scaling circuit, an electron tube having an anode, a cathode, a screen grid and a control grid, said anode being substantially isolated, a condenser, a source of potential connected through said condenser between said anode and said cathode, a series-connected glow discharge tube and first resistor connected to shunt said condenser, and a second resistor connected across said power supply, said second resistor having an adjustable contact connected to said screen grid whereby the scale of said scaling circuit may be varied.
